UNITED STATES PATENT OFFICE.

ADOLPHUS S. DENNIS, OF LAKewood, OHIO, ASSIGNOR TO UNDERWOOD TYPEWRITER COMPANY, OF NEW YORK, N. Y., A CORPORATION OF DELAWARE.

TYPE-WRITING MACHINE.

1,177,934.

Specification of Letters Patent.

Patented Apr. 4, 1916.

Application filed November 22, 1911. Serial No. 661,661.

To all whom it may concern:

Be it known that I, ADOLPHUS S. DENNIS, a citizen of the United States, residing in Lakewood, in the county of Cuyahoga and 5 State of Ohio, have invented certain new and useful Improvements in Type-Writing Machines, of which the following is a specification.

This invention relates to the special paper feeding devices of typewriting machines, 10 designed to facilitate the writing of bills and simultaneously recording them on a separate sheet or ledger leaf.

In billing machines the bill to be sent out 15 is inserted on the platen together with the tally or record sheet from the loose leaf ledger with a carbon sheet in between. It is desirable to have the items of the separate bills written closely together on the ledger 20 sheet so as to waste no space thereon. To do this, the platen is rotated backwardly a predetermined distance after each bill is written, to a position permitting the completed bill to be removed and a new bill 25 placed on the machine, the platen being then rotated forwardly to carry the new bill with the same ledger sheet up to the proper printing point. In this operation the platen is rotated forwardly a distance determined by 30 the depth of the bill head, or the distance of the first typewritten line from the upper edge of the bill, and is rotated backwardly a less distance, the greater forward rotations providing for spacing on the ledger sheet, 35 the entries of succeeding bills.

An object therefore of my invention is to improve and simplify the means for rotating the platen so as to feed the paper, and cause the proper spacing of the tally sheet or 40 ledger leaf, and so that it may also be used to feed envelops.

In the preferred form of the invention, 45 the crank is mounted on a sleeve projecting through the casing, the sleeve carrying a detent which floats idly over a (toothed) crown gear. By adjusting a cam formed on the retaining wall or casing, the detent may be locked to the crown gear, so that the gear may travel over a predetermined distance 50 with the crank. It will be seen that this forms a clutch for connecting the crank with the body portion of the crown gear, which is effective for a portion of the revolution of the crank. The extent of the effective connection can be adjusted, to correspond to the

extent of movement of the platen desired, by changing the position of the adjustable cam. The crown gear in turn is connected to the platen axle by an adjustable means, so as to rotate the platen a variable amount on the 60 return movement of the crank, so that a certain amount of space may be lost, so as to uncover the last line of writing on the ledger sheet on the subsequent feeding of the following bill or item sheet. The invention 65 may also be used for feeding envelops *seriatim* over the platen, or for other work in which intermittent rotations in the same direction are imparted to the platen. When thus used, the crank is given a complete rotation in a forward direction at each operation, the platen being thereby rotated an extent determined by the position of the adjustable cam. A spring detent yieldingly holds the crank in its normal position of 70 rest, but permits it to be moved beyond said position in either direction.

Other features and advantages will hereinafter appear.

In the accompanying drawings, Figure 1 80 is a fragmentary view showing the device attached to a carriage of a typewriter. Fig. 2 is a vertical section. Fig. 3 is a vertical section on line 3—3 of Fig. 2, partly broken away to disclose the underlying structure 85 and showing the crank starting on its movement in a direction to rotate the platen backwardly. Fig. 4 is a vertical section on line 4—4 of Fig. 2, showing the detent and cams 90 in their normal position. Fig. 5 is a vertical section on the line 5—5 of Fig. 2, and shows the means for determining the distance to be lost in the movement of the crank in a direction to rotate the platen backwardly. Fig. 6 is a detail perspective view of the 95 cams. Fig. 7 is a front view of the device with parts in cross section and parts omitted, showing the relative position of the detent to the crown gear when not in clutching engagement therewith. Fig. 8 is a view 100 similar to Fig. 3, showing the crank at an intermediate position during the backward rotation of the platen thereby, with all parts in their proper relative positions. Fig. 9 is a right end view, showing the pin and scale 105 for setting the feeding device for a certain number of lines. Fig. 10 is a detail view of the crown gear.

The usual platen 1 of the Underwood typewriter is mounted on an axle 2 jour- 110

naled in the bushings 3, 4, of the inside carriage 5 held to the main carriage, which is not shown, by the lift hooks 6. Fastened at one end of the axle 2 is a finger knob 7, by means of which the platen may be moved in either direction an unlimited extent. At the left end, between the bushing 4 and the finger knob 7, the regular paper line-spacing mechanism is found, consisting of a ratchet 8 fast on the axle 2, moved intermittently by a pawl 9 and held in position by a detent 10. At the opposite end of the axle 2 projecting beyond the carriage 5, a cup 11 is held by a pin 12 extending through its hub 13 and the axle 2. Mounted loosely on the hub 13 for adjustment around the hub is a disk 14 having an arm 15 carrying a cup 16. Projecting through this cup 16 is a pin 17 adapted to be projected through any one of a series of holes 22 in the cup 11. The pin 17 has a cap 18 by which it may be grasped, so as to be drawn against the action of a coil compression spring 19 anchored against the wall 20 of the cup 16 and a shoulder 21 on the pin 17. When this pin is withdrawn from a hole 22 in the cup 11, Fig. 5, it may be reset in one of the other holes 22, enlarging or decreasing the distance between the movable pin 17 and a pin 23 fixed to the cup 11.

Operating between the pins 17 and 23 carried by the cup 11, is another pin 24 fixed in the body of a crown gear 25. This crown gear 25 is mounted loosely on the axle 2 and floats between the limitations of the pins 17 and 23, but is normally held with the pin 24 against the pin 23 by the tension of a coil spring 26 anchored at its ends in a slot 27 in the crown gear 25 and to a pin or stud 28 on the axle 2. Across the face of the teeth 29 of the crown gear 25 rides a detent 30. This detent 30 (Fig. 4) is pivoted by pins 31, 32, to the hub 33. This hub 33 revolves loosely on the axle 2, and protrudes through a casing or cam disk 34, so that an actuator in the form of a crank 35 may be fastened to the hub. It will now be seen that by rotating the crank 35, the detent 30 will be forced out by the cam surfaces of the teeth 29 which are pointed. Therefore, to connect the driving power of the crank 35, the detent 30 is jammed between two teeth by a means which will now be described. A second cam disk 36, loosely mounted on the hub 33, is held against turning, by a pin 38, fixed on a stationary casing 39, and resting in a slot 40 in the disk 36. To connect the cam disk 34 to the cam disk 36, and thus hold the disk 34 stationary, the latter is provided with a movably mounted spring-pressed pin 42, which is similar in construction to the pin 17, and is adapted to engage in any one of a plurality of holes 41 in the disk 36, so that the relative positions of the cam disks may be varied. The cam disks 34

and 36 have respectively cams 43 and 37, which are concentrically arranged with respect to each other and in close juxtaposition, so that the extent to which they overlap can be varied by a relative movement of the disks 34 and 36, and thus the combined effective extent of camming surface can be varied. In other words, the cam portion 43 of the disk 34 is constructed on the edge of the said disk, while the cam portion 37 of the disk 36 is slightly away from the edge, so as to allow the camming surface 43 to slide by, in order to telescope the two camming surfaces and reduce their length of action upon the detent 30. A slot 44 in the disk 34 is for assembling purposes only, to admit the disk being placed below the pin 38.

To provide a definite starting and stopping point for the movement of the crank, and to insure uniformity of operation, a hollow 45 is made in the casing 39 fast to the disk 46, held against rotating by the screw 47 in the stud 48 on the inside carriage 5. Into this hollow 45 a detent roll 49 on a plate 50 is forced by a spring 51, anchored to a pin 52 in the crank 35 and a stud 53 on the plate 50. The plate 50 has two slots 54, 55, through which studs 56 and 57 pass, allowing a sliding movement of the plate 50. As the detent roll 49 is held with a yielding pressure in the hollow 45, the crank may, if desired, be carried beyond the stopping point and the platen thus rotated indefinitely in either direction.

For the purpose of indicating the relative positions of the cams 43 and 37, the disk 34 is provided with a series of gradations, indicated at 60, which form a scale located in juxtaposition to the overlapping margin of the casing 39, which is provided with a reference mark 61 showing the relative adjustment of the cam disk 34 to the casing 39, and thus indicating the extent of overlapping of the cams 43 and 37. Means is also provided to indicate the number of lines which the mechanism will space at each actuation thereof, which consists in a graduated scale 62 provided on the periphery of the cup 11, which has located in juxtaposition thereto a reference mark 63 on the adjustable pin 17. This shows the amount which the pin 24 will move idly before coming in contact with the pin 17, and thus the amount or number of lines which the ledger will be spaced between the writing of two successive bills.

In the operation we will assume that it is desired to start a fresh ledger sheet with the first bill. The ledger sheet and the bill are placed together with a carbon sheet in between so that they enter at the right of the platen. The crank 35 is moved to the right (looking at Fig. 5) one complete revolution, and the detent 30 which is permanently connected to travel with the crank, at first rides over the teeth 29 of the crown gear 25, until

it reaches the cam portion 43 of the disk 34. The detent will now be forced into the cavity between two teeth and held there, so that on further travel it will drive or carry the crown gear 25 with it. The crown gear 25 will in turn immediately push the cup 11 along because the pin 24 on the crown gear is in contact with the pin 23 in the cup 11, and thereby cause the platen to rotate. As 10 the crank approaches the end of its complete revolution, the detent 30 will snap off of the free extremity of the cam 37, so that a continued rotation of the crank will enable the beveled teeth 29 to force the detent out of 15 engagement therewith, enabling the detent 10 to lock the platen 1 in position; the crank 35 continuing until it has completed its revolution when the roller 49 comes to rest in the socket 45. The crown gear 25 has its 20 teeth arranged in accord with those of the ratchet 8 of the regular line space mechanism, so as to coincide with the resting positions of the detent 10. The bill and ledger sheet have now been advanced to a position 25 where they can be written on, and after this operation, the platen may be rotated backwardly to a position such that the bill can be removed from the platen, leaving the ledger sheet still on the platen. This backward rotation of the platen is effected by a 30 rotation of the crank or actuator 35 in the opposite direction from that just described. The crank 35, on being rotated as indicated by the arrow shown in Fig. 3, will carry the 35 detent 30 as before, idly over the teeth 29 of the crown gear 25, until again cammed in, this time by the cam 37 on the disk 36. The crown gear 25 will then be carried along with the crank, first winding up on the 40 spring 26, until the pin 24 comes into engagement with the pin 17, when a positive connection will be made through the cup 11 to the platen axle 2, so that the platen can be rotated backward to enable the bill sheet 45 to be slipped from the platen. The extent of this rotation will then be determined by the point where the detent 30 slips off the free end of the cam 43; the crank 35 continuing its movement beyond this point until 50 it has made a complete reverse revolution with the roller 49 once more entering the socket 45.

With the freeing of the detent 30 from the cam 43 and the teeth 29, not only will the 55 platen 1 stop its movement but the spring 26 will be free to act so as to carry the crown gear 25 and bring the pin 24 once more into engagement with the pin 23, in order to enable the platen on a subsequent rotation of 60 the crank 35, to be immediately picked up and rotated in a line-feeding direction just so soon as the detent 30 is cammed in between the teeth 29 of the gear 25.

It will be noted that the extent which the 65 ledger sheet and the bill sheet are fed on to

the platen, will be determined by the period which the detent is locked between the teeth 29 of the crown gear 25, and that this in turn depends upon the combined effective camming length of the cams 37 and 43. Hence, 70 it will be evident that the extent which the bill sheet is fed to avoid the bill-head, so as to bring a clear space thereon opposite the printing point of the typewriter, may be regulated by regulating the combined effective camming length of the cams 37 and 43. This, as will be evident from the above description, is done by adjusting the position of the pin 42 in the various holes 41. It will be further evident that when the crank is 80 reversed to remove the bill sheet from the platen, a lost motion takes place before the spring 26 is wound up sufficiently to bring the pin 24 into engagement with the pin 17. During this time, the platen 1, of course, is 85 stationary, so that it has not had as much counter-rotation for a single revolution of the crank 35, as it had in placing the bill sheet on the platen. It is therefore apparent that the ledger sheet instead of being 90 returned its full distance which it was advanced by the initial rotation of the crank 35, will be only returned a fraction of this distance, so that when it is subsequently re-fed with a fresh bill sheet, instead of the last 95 typewritten line which was at the printing point coming once more to the printing point, a fresh line of the ledger sheet will be advanced to the printing point. The extent of this feed between two successive bill 100 sheets, that is to say, the distance between the last printing line and the new printing line on the ledger sheet, will be determined by the extent of play, or, in other words, by the distance between the pins 23 and 17. It 105 will thus be seen that by varying the position of the pin 17, the extent which the ledger sheet will be fed up between the writing of two bills, will depend on the position of the pin 17, which can be adjusted by placing it in any one of the holes 22, to vary the space between the written items of two separate bills as inscribed on the ledger sheet.

Variations may be resorted to within the scope of the invention, and portions of the 115 improvements may be used without others.

Having thus described my invention, I claim:

1. The combination with a platen, of an actuator rotatable about the platen axis for 120 rotating said platen, means for connecting said actuator to said platen to rotate said platen a certain extent in one direction and a different extent in the opposite direction, and adjustable means for varying the difference in the extent of rotation in one direction from the other direction.

2. The combination with a platen, of a coaxial actuator for rotating said platen, means for connecting said actuator to said 130

- platen to rotate said platen a certain extent in one direction and a different extent in the opposite direction, adjustable means for varying the difference in the extent of rotation in one direction from the other direction, and means for indicating the difference in extent of rotation.
3. The combination with a platen, of an actuator for rotating said platen, means for connecting the actuator to said platen to rotate said platen a certain extent in one direction and a different extent in the opposite direction, a permanently fixed member, and a spring-pressed detent on said actuator for engaging said fixed member acting solely to determine the starting and finishing point of said actuator.
4. The combination with a platen, of an actuator for rotating said platen, means for connecting said actuator to said platen, including a clutch, and overlapping cams for automatically forcing the parts of said clutch into engagement for a predetermined movement of said actuator.
5. The combination with a platen, of an actuator for rotating said platen, means for connecting said actuator to said platen, including a clutch, juxtaposed cams for automatically connecting the parts of said clutch for a predetermined movement of said actuator, and means for varying the effective extent of said cams.
6. The combination with a platen, of an actuator for rotating said platen, means for connecting said actuator to said platen, including a clutch, and juxtaposed cams for automatically connecting the parts of said clutch for a predetermined movement of said actuator; said cams being adjustable to overlap each other varying amounts to vary their combined effective magnitude.
7. The combination with a platen, of an actuator for rotating said platen, means for connecting said actuator to said platen, including a clutch, juxtaposed cams for automatically connecting the parts of said clutch for a predetermined movement of said actuator; said cams being adjustable to overlap each other varying amounts to vary their combined effective magnitude, and means for indicating the relative adjustment of said cams.
8. The combination with a platen, of an actuator for rotating said platen, means for connecting said actuator to said platen, including a clutch, juxtaposed cams for automatically connecting the parts of said clutch for a predetermined movement of said actuator; said cams being adjustable to overlap each other varying amounts to vary their combined effective magnitude, and means for locking said cams in any relative adjusted positions.
9. The combination with a platen, of an actuator for rotating said platen, means for connecting said actuator to said platen, including a clutch, cam disks having juxtaposed cams thereon for automatically connecting the parts of said clutch for a predetermined portion of the movement of said actuator, said cam disks being adjustable to vary the combined effective magnitude of said cams and thus the period of connection of the parts of said clutch, one of said cam disks having a series of openings thereon, and a pin movably mounted in the other of said disks and adapted to engage in one of said openings to determine the relative positions of said cams.
10. The combination with a platen, of an actuator for rotating said platen, means for connecting said actuator to said platen, including a clutch, cam disks having juxtaposed cams thereon for automatically connecting the parts of said clutch for a predetermined portion of the movement of said actuator, said cam disks being adjustable to vary the combined effective magnitude of said cams and thus the period of connection of said clutch parts, one of said cam disks having a series of openings therein, and a spring-pressed pin mounted in the other of said disks and adapted to engage in one of said openings to lock said disks together.
11. The combination with a platen, of an actuator for rotating said platen, means for connecting said actuator to said platen, including a clutch, cam disks having juxtaposed cams thereon for automatically connecting the parts of said clutch for a predetermined portion of the movement of said actuator, said cam disks being adjustable to vary the combined effective magnitude of said cams and thus the period of connection of said clutch parts, and means for holding one of said cam disks fixed.
12. The combination with a platen, of an actuator for rotating said platen, means for connecting said actuator to said platen, including a clutch, cam disks having juxtaposed cams thereon for automatically connecting the parts of said clutch for a predetermined portion of the movement of said actuator, said cam disks being adjustable to vary the combined effective magnitude of said cams and thus the period of connection of said clutch parts, means for holding one of said cam disks fixed, and means for locking the other of said cam disks to said fixed cam disk.
13. The combination with a platen, of an actuator for rotating said platen, means for connecting said actuator to said platen, including a clutch, and a plurality of concentric cams for automatically connecting the parts of said clutch for a predetermined portion of the movement of said actuator, said cams overlapping each other and being rotatable relative to each other to vary their combined effective magnitude, and thus the

period of connection of the parts of said clutch.

14. The combination with a platen, of an actuator for rotating said platen, a toothed gear having a limited rotation relative to the platen, means for connecting said gear to said platen, a detent movably connected to said actuator, the teeth of said gear being formed to automatically disconnect said detent therefrom, and a cam for forcing said detent into engagement with said teeth during a certain portion of the revolution of said detent with said actuator.

15. The combination with a platen, of an actuator for rotating said platen, a crown gear, means for connecting said crown gear to said platen, a detent movably connected to said actuator, the teeth of said crown gear being formed to automatically disconnect said detent therefrom, and a plurality of cams for forcing said detent into engagement with said crown gear for a certain portion of the revolution of said actuator, said cams being adjustable relative to each other to vary their combined effective magnitude, and thus vary the period of connection of said detent with said crown gear.

16. The combination with a platen, of an actuator for rotating said platen, a crown gear, means for connecting said crown gear to said platen, a detent movably connected to said actuator, the teeth of said crown gear being formed to automatically disconnect said detent therefrom, a plurality of cams for forcing said detent into engagement with said crown gear for a certain portion of the revolution of said actuator, said cams being adjustable relative to each other to vary their combined effective magnitude, and thus vary the period of connection of said detent with said crown gear, and means for indicating the relative adjustment of said cams.

17. The combination with a platen, of an actuator for rotating said platen, a crown gear, means for connecting said crown gear to said platen, a detent movably connected to said actuator, the teeth of said crown gear being formed to automatically disconnect said detent therefrom, a plurality of cams for forcing said detent into engagement with said crown gear for a certain portion of the revolution of said actuator, said cams being adjustable relative to each other to vary their combined effective magnitude, and thus vary the period of connection of said detent with said crown gear, and means for locking said cams in their relative adjusted positions.

18. The combination with a platen, of an axle for said platen, an actuator for rotating said platen, a member connected to said actuator, a spring connecting said member to said axle permitting a relative yielding motion between said member and said axle,

and means for positively connecting said member to said axle.

19. The combination with a platen, of an axle for said platen, an actuator for rotating said platen, a member loosely mounted on said axle and connected to said actuator, a spring for connecting said member to said axle in a yielding manner, and means for positively connecting said member to said axle having a certain amount of play or lost motion.

20. The combination with a platen, of an axle for said platen, an actuator for rotating said platen, a member loosely mounted on said axle, means to connect said actuator to said member, a spring for connecting said member to said axle in a yielding manner, means for positively connecting said member to said axle having a certain amount of play or lost motion, and means for varying the extent of said play or lost motion.

21. The combination with a platen, of an axle for said platen, an actuator for rotating said platen, a member loosely mounted on said axle and connectible to said actuator, a spring for connecting said member to said axle in a yielding manner, means for positively connecting said member to said axle having a certain amount of play or lost motion, and means for varying and indicating the extent of said play or lost motion.

22. The combination with a platen, of an axle for said platen, a pin connected to said axle, an actuator for said platen loosely mounted on said axle, a pin connectible to said actuator, and a pin adjustably connected to said axle, so as to vary its relative position to said first-mentioned pin, said second-mentioned pin being adapted to swing between said first-mentioned pin and said third-mentioned pin, to allow a variable amount of play between said actuator and said platen.

23. The combination with a platen, of an axle for said platen, a pin connected to said axle, an actuator for said platen loosely mounted on said axle, a pin connectible to said actuator, a pin adjustably connected to said axle, so as to vary its relative position to said first-mentioned pin, said second-mentioned pin being adapted to swing between said first-mentioned pin and said third-mentioned pin, to allow a variable amount of play between said actuator and said platen, and a spring normally tending to keep said second-mentioned pin in contact with one of the others of said pins.

24. The combination with a platen, of an axle for said platen, a pin connected to said axle, an actuator for said platen loosely mounted on said axle, a pin connectible to said actuator, and a pin adjustably connected to said axle, so as to vary its relative position to said first-mentioned pin, said second-mentioned pin being adapted to swing be-

tween said first-mentioned pin and said third-mentioned pin, to allow a variable amount of play between said actuator and said platen, and a spring connected to said axle adapted to tend to keep said second-mentioned pin in contact with said first-mentioned pin.

25. The combination with a platen, of an axle for said platen, a pin connected to said axle, an actuator for said platen loosely mounted on said axle, a pin connectible to said actuator, a third pin connected to said axle and located in spaced relation from said first pin, permitting a limited movement of said second pin between said first and third pins, and means for connecting said second pin with said actuator during a certain portion of the movement of said actuator.

26. The combination with a platen, of an axle for said platen, a pin connected to said axle, an actuator for said platen loosely mounted on said axle, a pin connectible to said actuator, a third pin connected to said axle and located in spaced relation from said first pin, permitting a limited movement of said second pin between said first and third pins, means for connecting said second pin with said actuator during a certain portion of the movement of said actuator, and a spring connected to said axle and to said second-mentioned pin so as to yieldingly permit the movement of said second-mentioned pin out of contact with said first-mentioned pin and so as to return said second-mentioned pin into contact with said first-mentioned pin at the disconnection of said second-mentioned pin from said actuator.

27. The combination with a platen, of an actuator for said platen, a loosely mounted member, means for intermittently connecting said member to said actuator, means for connecting said member to said platen permitting a certain amount of play between said member and said platen, and a spring for taking up said play during the period of disconnection of said member from said actuator.

28. The combination with a platen, of an axle for said platen, a cup secured to said axle, a pin mounted in said cup, a crown gear loosely mounted on said axle, a pin mounted on said crown gear, and engaging with said first-mentioned pin, a detent, an actuator connected to said detent, said crown gear having teeth adapted to engage said detent to lock said crown gear in driving relation with said actuator, and means for forcing said detent in clutching relation with said crown gear.

29. The combination with a platen, of an axle for said platen, a cup secured to said axle, a pin mounted in said cup, a crown gear loosely mounted on said axle, a pin mounted on said crown gear and engaging

with said first-mentioned pin, a detent, an actuator connected to said detent, said crown gear having teeth adapted to engage said detent to lock said crown gear in driving relation with said actuator, and a cam for forcing said detent in clutching relation with said crown gear.

30. The combination with a platen, of an axle for said platen, a cup secured to said axle, a pin mounted in said cup, a crown gear loosely mounted on said axle, a pin mounted on said crown gear and engaging with said first-mentioned pin, a detent, an actuator connected to said detent, said crown gear having teeth adapted to engage said detent to lock said crown gear in driving relation with said actuator, a cam for forcing said detent in clutching relation with said crown gear, a spring for normally holding said second pin in contact with said first pin, and a third pin located in spaced relation from said first pin on the opposite side of said second pin.

31. The combination with a platen, of an axle for said platen, a cup secured to said axle, a pin mounted in said cup, a crown gear loosely mounted on said axle, a pin mounted on said crown gear and engaging with said first-mentioned pin, a detent, an actuator connected to said detent, said crown gear having teeth adapted to engage said detent to lock said crown gear in driving relation with said actuator, a cam for forcing said detent in clutching relation with said crown gear, a spring for normally holding said second pin in contact with said first pin, and a third pin located in spaced relation from said first pin on the opposite side of said second pin; said third mentioned pin being adjustably secured to said cup so as to vary the amount of play between said cup and said crown gear.

32. The combination with a platen, of an axle for said platen, a cup secured to said axle, a crown gear mounted on said axle, a pin secured to said cup, a pin secured to said crown gear, a spring normally forcing said second-mentioned pin in contact with said first-mentioned pin, a third pin connected to said cup in spaced relation from said first-mentioned pin and on the opposite side of said second-mentioned pin, so as to permit a limited play between said cup and said crown gear, a crank, a hub connected to said crank, a detent pivotally mounted on said hub and engaging with said crown gear, a plurality of relatively adjustable cams for forcing said detent into engagement with said crown gear during a portion of the movement of said crank, and means for adjusting said cams relative to each other to vary the period of connection of said detent with said crown gear.

33. The combination with a platen, of a pair of stops located in spaced relation and

connected fixedly to said platen, an actuator for rotating said platen, a clutch enabling the connection of said actuator with said platen, and a pin connected to one of the elements of said clutch and adapted to oscillate between said stops so as to provide a limited amount of relative movement between said actuator and said platen.

34. The combination with a platen, of an axle for said platen, a cup secured to said axle, a pin secured to said cup, a crown gear mounted on said axle, a pin secured to said crown gear, a spring connected to said axle and said crown gear tending normally to force said second-mentioned pin in contact with said first-mentioned pin, said cup having a series of openings therein, a pin movable into any one of said openings and positionable at variable distances on the opposite side of said second-mentioned pin to said first-mentioned pin, so as to permit a limited movement of said second-mentioned pin between said first and third-mentioned pins, a hub loosely mounted on said axle, a crank secured to said hub, a detent pivotally mounted on said hub and engageable with said crown gear, a cam, means for fixedly securing said cam, a second cam arranged concentrically with said first cam and overlapping the same, said cams being located so as to force said detent into engagement with said crown gear during a portion of the movement of said detent with said crank, means for adjusting the relative position of said cams, so as to vary their combined effective magnitude, and means for determining the initial position of said crank.

35. The combination with a platen, of an actuator having a definite movement of fixed extent for rotating said platen, means for connecting said actuator to said platen so that the fixed rotation thereof will rotate said platen a certain extent in one direction and a different extent in the opposite direction, adjusting mechanism to vary said difference without varying the extent of movement of the actuator and detaining means for determining the starting and finishing point of said actuator.

36. The combination with a platen, of an actuator for rotating said platen, means for connecting and disconnecting said actuator to and from said platen including a clutch having parts connectible to determine the movement of said platen with said actuator, means for automatically connecting the parts of said clutch for a portion of the movement of said actuator, and means for varying the period of disconnection of said clutch by said first-mentioned means.

37. The combination with a platen, of an actuator for rotating said platen, means connecting said platen to said actuator for a predetermined portion of the movement of said actuator, and detaining means for re-

leasingably confining both the starting and finishing points of the movement of said actuator for each stroke to a certain point and permitting the actuator to be carried beyond said certain point.

70

38. The combination with a platen, of an actuator for rotating said platen, means connecting said platen to said actuator for a predetermined portion of the movement of said actuator, and locking means for coinciding the starting and finishing points of the movement of said actuator to a single point for a continuous action thereof.

75

39. The combination with a platen, of an actuator coaxial with the platen for rotating said platen, means for connecting said actuator to said platen, including a clutch, means for automatically connecting the parts of said clutch for a predetermined portion of the movement of said actuator and disconnecting the clutch parts for another portion of said movement, adjusting means for varying the period of disconnection of said clutch by said first-mentioned means, and means for indicating the adjustment of said second-mentioned means and thus the period of connection of said clutch.

80

40. The combination with a platen, of an actuator rotatable about the platen axis for rotating said platen, means for connecting said actuator to said platen, including a clutch having normally disengaged parts connected respectively to the actuator and platen axis, and a stationary cam for automatically forcing the parts of said clutch into locked engagement and holding them in engagement for a predetermined portion of the movement of said actuator and then releasing the clutch and permitting a continued rotation of the actuator separate from the platen, said cam adjustable to vary the period of engagement of the clutch parts.

85

41. The combination with a rotatable platen, of an actuator rotatable about the platen axis, a yielding stop for the actuator for determining the normal limits of rotation of the actuator, and driving mechanism between the actuator and platen to effect a predetermined rotation of the platen, said actuator being rotatable in either direction beyond its normal limits determined by said stop to effect a greater rotation of the platen.

90

42. The combination with a rotary platen, of an actuator rotatable about the platen axis, and a spring detent to yieldingly hold the actuator at a normal limit of movement but permitting the actuator to be carried beyond said normal limit in either direction.

105

43. The combination with a platen, of an actuator to rotate the platen in both directions, said actuator having a definite normal range of movement in both directions, automatic means for maintaining said platen

130

- free from said actuator at both the beginning and end of said movement of the actuator and for connecting said platen to move with said actuator a predetermined distance 5 in one direction intermediate the beginning and end of said movement of the actuator in one direction, and a different distance in the opposite direction during the reverse movement of the actuator, means to vary 10 said distances of rotation of the platen without varying the said range of movement of the actuator, and means to stop and hold the actuator at the limits of its movement.
44. The combination with a platen, of an actuator having a limited normal movement, detaining means to determine the limits of said movement, automatic means for maintaining said platen free from said actuator at both the beginning and end of 15 said movement of said actuator and connecting said platen to move with said actuator a predetermined period intermediate the beginning and end of said movement, and adjusting means for varying the extent of 20 said period of action without varying said limits of movement of the actuator; said actuator being movable in either direction beyond the limits determined by said detaining means and thereby operable to effect a 25 further rotation of the platen.
45. The combination with a platen, of an actuator rotatable about the platen axis and having a definite normal range of movement for rotating said platen, means for connecting 30 said actuator to said platen to rotate as a unit therewith, said means including a clutch, means for automatically connecting the parts of said clutch so that the actuator has a fixed relation to the platen during a predetermined portion of the movement of 35 said actuator and for disconnecting the clutch parts when the actuator is at an intermediate point during said movement so that the actuator can rotate free of the platen during the final portion of said movement, and adjusting means for varying the point of disconnection of said clutch.
46. The combination with a rotatable platen, of an actuator rotatable about the 40 platen axis for rotating the platen, a clutch to connect the actuator to the platen, and a spring detent for yieldingly holding the actuator to normally limit the movement of the actuator and thereby determine the extent of rotation of the platen; said actuator being movable in either direction from the position in which it is held by said detent, to effect a greater rotation of the platen than that determined by said detent.
47. The combination with a rotary platen, of an actuator rotatable about the platen axis, a clutch to effect a fixed connection between the platen and actuator to rotate the platen, retarding means for the actuator 45 for normally limiting the movement of the

actuator in opposite directions, and mechanism between the actuator and platen for effecting a greater rotation of the platen in one direction than the other when the actuator is reciprocated between said normal limits; said retarding means being yieldable to permit the actuator to be moved in either direction beyond said limits and thereby permit rotation of the platen through any desired angle.

48. The combination with a platen, of an actuator rotatable about the platen axis, a clutch between said actuator and the platen comprising clutch parts connected to the actuator and platen respectively for rotation about the platen axis as a center, and means for intermittently connecting the clutch parts when the actuator is rotated continuously and thereby intermittently rotating the platen, the connection between 85 one of the clutch parts and the part to which it is connected comprising a lost motion spring connection for effecting shorter intermittent rotations of the platen when the actuator is rotated in one direction 90 than when it is rotated in the other direction.

49. The combination with a rotatable platen, an actuator therefor, and an intermediate member, all having a common axis 95 of rotation, of means for normally holding the actuator at rest in a predetermined position, permitting the platen and said member to rotate independently thereof, said member having a lost motion connection 100 with the platen permitting a limited rotation of the said member relatively to the platen, and means operable when the actuator is rotated in one direction from said position of rest, to automatically connect it 105 with said member and rotate the latter a predetermined fixed distance and then disconnect the actuator from said member, said connecting means also operable to connect the actuator to said member when the actuator is rotated in the reverse direction, and thereby to rotate the said member said predetermined distance in the reverse direction 110 and then release the actuator, leaving the platen free for rotation independently of 115 the actuator, said member being arranged to rotate relatively to the platen the distance permitted by said lost motion connection while the actuator is rotating said member in one direction but arranged to positively 120 drive the platen the full distance through which said member is rotated by the actuator in the reverse direction, whereby the platen is rotated a definite distance in one direction by the actuator and a different 125 distance in the other direction.

50. The combination with a rotary platen, of an actuator therefor rotatable about the platen axis, a clutch between the platen and said actuator, comprising clutch parts con- 130

nected, respectively, to the platen and said actuator, one of said connections permitting a limited lost motion between the clutch part and the part to which it is connected, 5 said actuator having a normal position of rest in which the clutch parts are disconnected to permit the platen to be rotated independently of the actuator, means operable when the actuator is rotated in one 10 direction from said position of rest, to connect the clutch parts to drive the platen through a predetermined distance and then disconnect the clutch parts, permitting the platen to be rotated independently of the 15 actuator, said connecting means also oper-

able, when the actuator is rotated in the reverse direction, to connect the clutch parts during the rotation of the actuator said predetermined distance and then disconnect the clutch parts, and means whereby said lost 20 motion is effected during the rotation of the actuator in one direction only, thereby causing the platen to be rotated by the actuator a greater distance in one direction than in the other direction.
